(Cl. D34—1)

To all whom it may concern:

Be it known that I, Louise Ross Laskey, a citizen of the United States, residing at Kew Gardens, Long Island, in the county of Queens and State of New York, have invented a new, original, and ornamental Design for a Toy Locomotive, of which the following is a specification, reference being had to the accompanying drawing, forming part thereof.

In the drawing:

Fig. 1 is a side elevational view of a toy locomotive, showing my new design.

Fig. 2 is a top plan view thereof.

I claim:

The ornamental design for a toy locomotive, substantially as shown.

LOUISE ROSS LASKEY.
